UNITED STATES PATENT OFFICE.

FRANZ LANG, OF STUTTGART, GERMANY, ASSIGNOR TO ACRO AKTIENGESELLSCHAFT,
OF KUSSNACHT AM RIGI, SWITZERLAND.

INTERNAL-COMBUSTION ENGINE.

Application filed November 6, 1925, Serial No. 67,830, and in Germany November 29, 1924.

Two—or more—cylinder combustion engines for two or more cycles and adapted for dislodging action are known, in which the dislodging piston and the working piston are 5 constructed as two individual pistons, adapted to transmit motion during the expansion stroke and reciprocating in two cylinders, inclined towards each other. Between the two cylinders, besides the main connecting channel, a second overflow channel is arranged in 10 such a manner, that at the end of the compression stroke the main connection channel is covered by the dislodging piston and consequently the air or gases present above said 15 piston are further compressed and forced through the overflow channel into the other cylinder for the purpose of introducing and mixing the fuel.

In the known engines of this kind the fuel 20 is introduced before each working stroke into a recess of the connecting channel between two cylinders, which channel leads the air current during the last part of the compression stroke; said connecting channel having 25 uniform width at all parts with the exception of the recess. The fuel quantity introduced into the connecting channel, however, mixes only insufficiently with the air flowing through said channel, the fine fuel particles 30 being driven in front of the air current as by a piston, without mixing with the air, so that at least the starting of the engine is rendered difficult and in most cases the combustion remains incomplete.

These drawbacks are obviated by this invention, by virtue of which the compressed air-channel is provided with a throttling restriction through which the air current, passing 35 through the channel towards the end of the compression stroke, flows together with at least a portion of the fuel injected into the channel. At least a portion of the fuel injected only towards the end of the compression stroke enters into contact with the current of air, which has been strongly heated 40 by compression, already in advance of the restriction, and, while passing through said restriction, is so intimately intermixed with the air that self-ignition takes place.

The invention, with these objects in view, 45 consists in forming the overflow-channel in the form of a double nozzle, the narrowest portion of each component nozzle being at or adjacent to the point where the mouth of the 50 fuel-injecting nozzle is located. By such ar-

angement the compressed air is fed with accelerating speed and at the proper time to the point of fuel-admission, and in such a manner that the compressed air is thoroughly mixed with the fuel-veil or mist issuing from 60 the fuel-injecting nozzle, thereby forming a readily ignitable mixture.

In the accompanying drawing one form of construction of my improved combustion engine is illustrated in a diagrammatical 65 manner in vertical section.

In the drawing the reference characters *a* and *b* indicate the two cylinders, while the two pistons are indicated by *c* and *d* and the combustion spaces by *e* and *f*. The overflow 70 channel is constructed as a double nozzle *g*, that is to say, as two tapering conduits or funnels whose restricted mouths meet at a point *h* at an intermediate point between the two cylinders, a fuel-injecting nozzle *i* being 75 also arranged, at an intermediate point, as shown, to inject fuel at the prescribed times into the channel *g* at or in proximity to the constricted part *h* of said channel.

Eventually lateral auxiliary fuel injecting 80 nozzles *k* may be provided, as shown.

The two cylinder-spaces *e* and *f* are connected with each other, when the two pistons enter into the shown position of strongest compression, only by means of the channel *g*, 85 which is nozzle-like and restricted at the point *h*. At this restriction the fuel nozzle *i* is preferably arranged.

As the compression effected by the piston *c* towards the end of the compression-stroke 90 is greater than the compression effected by the piston *d*, air must pass from the space *e* to the space *f* through the channel *g*. This air current takes along with it through the restriction *h* at least a portion of the fuel injected 95 through the injection nozzle *i*. Thereby the fuel-particles are well mixed and whirled together with the heated air, so that the self-ignition of the mixture takes place and a working action is effected.

The injection-nozzle *i* must be arranged in the cylinder in such a manner that the air flowing from one cylinder to the other comes in contact with injected fuel at the latest at the restriction itself, or, still better, before 105 passing through said restriction.

With corresponding changes the arrangement of the overflow channel in form of a double nozzle can be employed for cylinders arranged abreast of each other and provided 110

with two crank shafts or for engines, the pistons of which reciprocate in opposite directions, or for radial- and multiple-cylinder- engines.

5 I claim:

1. A combustion engine, comprising, in combination a pair or plurality of pairs of cylinders, a main connection channel between each pair of cylinders, a further overflow channel between said pair of cylinders and a nozzle adapted to feed the fuel to said overflow channel, the latter being shaped in the form of a double nozzle, the narrowest parts of which are at or adjacent to the injection 10 nozzle.

15

2. In a combustion engine comprising two cylinders and pistons working therein at different degrees of compression, a channel for conveying compressed air from the combustion space of one cylinder toward that of the other, said channel being formed as two tapering conduits whose restricted portions meet at an intermediate point between the two cylinders in combination with means for injecting fuel into said channel also at an 20 intermediate point.

In testimony whereof I have hereunto affixed my signature.

FRANZ LANG.
